United States Patent Office.

JUNIUS SCHENCK, OF NEW YORK, N. Y.

Design No. 2,950, dated March 10, 1868.

DESIGN FOR A TRADE-MARK.

The Schedule referred to in these Letters Patent and making part of the same.

TO ALL WHOM IT MAY CONCERN:

Be it known that I, JUNIUS SCHENCK, of New York, in the county and State of New York, have originated a new Design for a Trade-Mark, of which the following is a full, clear, and exact description, reference being had to the accompanying drawing, making part of this specification.

The drawing represents a front view of my invention.

This invention relates to a new design for trade-mark, and consists of a Maltese cross, A, set upon a square, B, in such a manner that the angles of the square are between the arms of the cross, as is clearly shown in the drawing.

This trade-mark is designed to be used on a certain kind of patent combination hose, manufactured under my direction.

Having thus described my invention, what I claim as new, and desire to secure by Letters Patent, is—

The design for a trade-mark, consisting of the Maltese cross on the square, as set forth and shown.

JUNIUS SCHENCK.
